BEDCLOTHES LIFTING AND SUPPORTING DEVICE

Rudolph T. Eeklund, Aitkin, Minn.

Application April 5, 1948, Serial No. 18,967

3 Claims. (Cl. 5—319)

1

This invention relates to a new and novel device adapted for use in connection with conventional beds for upwardly lifting and supporting the upper bedclothes out of contact with the bottom sheet usually placed directly over the mattress, thereby to relieve the feet or other portions of the body of an individual reposing in the bed of the weight of the bedding or bedclothes, which may at times be uncomfortable.

It is well known that some individuals have a tendency towards restlessness upon retiring at night whereby they may not be able to drop off to restful slumber for sometime after retiring. There are also individuals who suffer lack of sleep at night because of being more or less sensitive to the pressure imposed upon the body, particularly the feet, by the weight of the usual bedding or bedclothes placed over the individual's body. It is usually customary to tuck the bedding under the mattress at the foot end of the bed to retain the bedding in place thereon, and if one's feet are located close to the foot end of the bed, it may readily be understood that under such conditions the bedclothes may readily exert an uncomfortable restraining pressure upon the feet, particularly if the individual should attempt to lie on his back with his toes directed upwardly. Some individuals also desire rather heavy bedclothes during the winter season which may further add to the discomfort of the individual as a result of the added weight placed upon the feet or other portions of the body at night.

I have discovered from actual experience that by supporting the top bedding at an elevation above the individual's body, particularly at the foot of the bed, whereby complete freedom of movement is provided for the individual's feet, the average individual will, in most cases quickly assume a relaxed state upon retiring, which is conducive of sleep and may cause the individual to more quickly drop off to a sound restful slumber. It is therefore desirable that means be provided whereby portions of the usual bedding or bedclothes of a conventional bedstead may be conveniently upwardly lifted and supported in a position above the body of an individual lying in the bed as, for example, his feet, whereby the individual's feet are provided complete freedom regardless of any positions in which they may be placed.

An important feature of the present invention therefore is to provide a simple, highly efficient device for upwardly lifting portions of the top bedding or bedclothes of a conventional bed to thereby support such bedding out of direct con-

tact with a sleeper's body, particularly his feet, and whereby the sleeper's feet may be afforded complete freedom to move about at will without restraint, and without being subjected to the weight or pressure of the bedding thereon, which may be found to be extremely uncomfortable under certain conditions.

A future object of the invention resides in the provision of a simple inexpensive bedclothes-lifting device which is so constructed that it may readily be applied to a conventional bed to support the bedding in an elevated position, when desired, and when not required, may be lowered to an inoperative position whereby it may be concealed beneath the bedding so as not to detract from the appearance of the bed during the time the bed is not in use.

A further object is to provide a device of the class described comprising a member adapted to be positioned over a portion of a bed beneath the top bedclothes, and having means at its ends for adjustably securing it to the ends of the bedstead or bedspring, whereby the cross member may be raised or lowered to any desired position to support the bedding out of contact with a portion of an individual's body such as the feet.

A further object is to provide a bedclothes-lifting device comprising an arch-shaped member including a horizontal portion adapted to be positioned beneath the top bedclothes of the bed and the bottom or mattress sheet thereof, and said member having downwardly extending spaced legs operatively connected to suitable supporting devices, one at each side of the bed, having means for clampingly securing them to the side rails of the bed or the bedsprings, whereby the arch-shaped member may be swung upwardly to an upright operative position to lift the bedclothes upwardly out of contact with the bed or mattress sheet, to relieve a sleeper's body of the weight of the bedclothes, and also whereby when the bed is not in use, said arch-shaped member may be swung downwardly with its horizontal portion engaging the bottom sheet or mattress whereby it may readily be completely concealed by the top bedclothes when not in use.

Other objects of the invention reside in the unique construction of the mounting means for the arch-shaped member whereby said member may readily be attached to any conventional type of bed without the use of special tools or separate bolts, screws or other separable securing elements, and without marring the appearance of the bed; in the provision of an apparatus of this type which is extremely simple and inexpensive in

construction whereby it may be economically manufactured in quantity production at low cost; and in the provision of a bedclothes lifting and supporting device which is so constructed that it may readily and quickly be applied to a bed by an inexperienced person.

Other objects of the invention will appear from the following description and the accompanying drawings and will be pointed out in the annexed claims.

In the accompanying drawings there has been disclosed a structure designed to carry out the various objects of the invention, but it is to be understood that the invention is not confined to the exact features shown, as various changes may be made within the scope of the claims which follow.

In the drawings:

Figure 1 illustrates a conventional type of bed with an individual reposing thereon, and the invention being shown applied to the foot end of the bed and positioned to lift the bedding or bedclothes out of direct contact with the individual's feet;

Figure 2 is an enlarged view substantially on the line 2-2 of Figure 4, showing the device clampingly secured to side rails of a conventional bedspring and the arch-shaped bedding-engaging member being swung upwardly to an operative position, and having the lower terminals of its spaced side legs received in sockets provided in the supporting arms;

Figure 3 is a view similar to Figure 2 but showing the clamping means at the near or opposite side of the bed and the arch-shaped member being swung downwardly to an inoperative position;

Figure 4 is a view showing the arch-shaped member supported over a bed;

Figure 5 is a detail view of the arch-shaped member detached from its supporting arms;

Figure 6 is a detail sectional view on the line 6-6 of Figure 2;

Figure 7 is a plan view of a supporting arm having means for attaching it to the upper side rail of a bedspring and wherein the side rails of the bedspring are cylindrical in cross section, as illustrated in Figure 8;

Figure 8 is a detail sectional view on the line 8-8 of Figure 7;

Figure 9 is an enlarged detail view showing a simplified form of supporting arm wherein the outer end of the arm is not vertically adjustable, as in the construction illustrated in the previous figures;

Figure 10 is a sectional view on the line 10-10 of Figure 9;

Figure 11 is a view showing a supporting arm similar to the one illustrated in Figures 2 and 3, but adapted for mounting directly upon the side rails of a bedstead and not on the side rails of the bedspring;

Figure 12 is an end view of Figure 11 illustrating the clamping elements for detachably securing the bedding lifter to the side rails of the bedstead;

Figure 13 is a view showing a device comprising supporting arms similar to the ones illustrated in Figures 11 and 12, but wherein the supporting arms are pivotally mounted upon brackets provided at the ends of a light-weight skeleton frame adapted to be placed between the mattress and the bedspring, and which is particularly applicable for use in connection with box type bedsprings which do not have opposed side rails;

Figure 14 is an end view of one side of Figure 13 showing the supporting frame interposed between the mattress and the boxspring; and

Figure 15 is a view showing a bedclothes-engaging member comprising telescoping tubular sections whereby the member may be longitudinally adjusted to beds of different widths.

In the selected embodiment of the invention herein disclosed there is illustrated in Figure 1, for purposes of disclosure, a conventional bedstead comprising the usual head 2, foot end 3, and side rails 4, having their ends detachably secured to the head and foot ends of the bed, as is well known. The usual bedspring, generally designated by the numeral 5, is supported upon the side rails 4 of the bed in any well known manner, and is shown provided with upper and lower side rails indicated at 6 and 7 in Figure 1. The mattress 8 is shown supported directly upon the bedspring 5 and may be covered with a bottom or mattress sheet, as is well known, upon which an individual lies when reposing in the bed, as shown in Figure 1.

The novel means herein disclosed for lifting the bedclothes 9 out of direct contact with a portion of an individual's body as, for example, his feet 11, is shown comprising an arch-shaped member, generally designated by the numeral 12, having an upper horizontal portion 13 and downwardly directed legs 14-14. The member 12 may be constructed as illustrated in Figures 4 and 5, wherein it will be noted the side legs 14 may be formed of a suitable metal such as cast aluminum, and the upper horizontal bar 13 may be of wood or any other suitable material having its ends suitably secured to the legs 14, as shown.

The member 12 is adapted to be supported over the bed in an upright position, as shown in Figures 1 and 2, whereby it will upwardly lift and support the bedding at an elevation above the individual's feet when the feet are positioned with the toes directed upwardly.

To thus support the member 12 over the bed, suitable supporting arms 15 are detachably secured to the sides of the mattress or bedstead, as illustrated in the application drawings. In the form shown in Figures 1 to 4, inclusive, the arms 15 are shown designed for attachment to the upper side rails 6 of a bedspring, and wherein said side rails are of angle iron cross-section, as best illustrated in Figure 4. Each supporting arm 15 is shown having a socket member 16 pivotally mounted at its outer end by a suitable pivot pin or screw 17. The socket members 16 are open at both ends, and when they are vertically disposed as illustrated in Figure 2, the lower terminals 18 of the legs 14 of the arch-shaped member 12 may be inserted through said socket members and into fixed sockets 19 provided in the outer ends of the arms 15, as clearly illustrated in Figures 2 and 3.

The fixed sockets 19 retain the arch-shaped member 12 in its upright operative position, shown in Figures 1 and 2. When it is desired to lower the member 12 to its inoperative position, shown in Figure 3, the member 12 is slightly elevated relative to the socket members 16 to thereby lift the lower terminals 18 of its legs 14 out of the fixed sockets 19 of the arms 15, whereupon the member 12 may be swung downwardly to its inoperative position shown in Figure 3, without disturbing the adjustment or positions of the supporting arms 15. If desired, the arch-shaped member 12 may be completely removed from the bed by simply lifting the terminals of its legs

from the socket members 16, whereby the arch-shaped member may be stored away in an out of the way place, as will be understood by reference to Figure 5.

The lower ends of the supporting arms 15 are preferably pivotally mounted upon the bedspring 5 or upon the bedstead, whereby the outer ends of the supporting arms 15 may be vertically adjusted to properly position the arch-shaped member 12 with respect to the top of the mattress and whereby the bedding may be lifted to a position whereby it may be out of direct contact with that portion of the individual's body positioned directly beneath the horizontal portion or bar 13 of the member 12.

To thus adjustably mount the supporting arms 15 upon the bedspring, each arm is shown pivotally supported upon a suitable mounting bracket 21 having enlarged clamping faces 22, preferably circular in configuration and provided with circumferentially spaced corrugations or radical teeth 20, as illustrated in Figures 7 and 8, thereby to positively retain the arms in adjusted position when the adjusting hand wheels 23 are tightened, as will be understood by reference to Figure 8. The hand wheels 23 are received in threaded engagement with pivot bolts 24 having their headed ends received in suitable apertures provided in the mounting brackets 21.

The brackets 21 are shown provided with spaced legs 25 each of which pivotally supports a small clamping element 26 comprising a clamping screw 27. The clamping elements 26 and screws 27 are adapted to engage the angle side rails 6 of the bedspring, as best illustrated in Figure 4, whereby the supporting arms 15 may be conveniently secured to the bedspring, and also whereby their positions lengthwise of the spring may readily be varied to position the arch-shaped member 12 at any desired point along the length of the bed. The small clamping elements 26 are shown pivotally connected to the supporting brackets 21 to allow relative pivotal movement of the supporting arms 15 in an outward direction, as indicated by the dotted lines in the right-hand side of Figure 4, thereby to provide ample room at each side of the mattress 8 for making the bed or arranging the bedclothes thereon.

In some bedsprings the side and end rails thereof are cylindrical in cross section, as illustrated at 28 in Figure 8. When the bedding lifter herein disclosed is to be mounted upon such a bedspring, a U-shaped member 29, best illustrated in Figure 7, has its spaced legs 31 secured to the clamping elements 26 mounted in the spaced legs 25 of the mounting brackets 21 by inserting the terminals of said legs into suitable sockets at 32 in Figures 7 and 8. The U-shaped member 29 may be a relatively light-weight rod and is adapted to be interposed between the spring and mattress to thereby prevent the clamping elements 26 from relatively rotating upon the cylindrical side rails 28 of the bed spring, as will readily be understood by reference to Figure 8. If desired, a pair of independent rods, not shown, may be substituted for the U-shaped member 29.

Figures 9 and 10 illustrate a device which is relatively simpler in construction than the device shown in Figures 2 and 3, in that no means is provided for vertically adjusting the position of the arch-shaped member 12 with respect to the top of the mattress 8.

As best illustrated in Figure 9, the supporting arms, generally designated by the numeral 33, 75

are provided at their lower ends with spaced legs 34 to each of which is pivotally connected a clamping element 26, similar to the clamping elements shown in Figure 4. Clamping screws 35 are provided in the spaced legs 34 for securing the elements to the side rails 6 of the bedspring, as shown. The upper or outer end portions of the supporting arms 33 are shown constructed in a manner similar to the supporting arms illustrated in Figures 2 and 3, and the parts thereof will therefore be referred to by like numerals. The supporting arms shown in Figure 9 function in identically the same manner as the arms 15, when in operative position, and they are shown adapted for mounting on a bedspring having upper angle iron side rails.

In Figure 12 the device is shown applied to a bed equipped with a box spring 36, whereby the supporting arms of the bedding lifter cannot be secured directly to the bedspring. In such cases the supporting arms 15 may be mounted directly upon the side rails 37 of the bedstead, and to accomplish this, auxiliary clamping elements 38 are shown pivotally connected to the spaced legs 25 of the mounting brackets 21 in lieu of the clamping elements 26, shown in Figures 8 and 10.

Each auxiliary clamping element 38 is shown provided with a pair of fixed jaws 39 which may be integrally connected or tied together by a web 40, shown in Figure 11. Complemental jaws 41 are movably mounted upon the fixed jaws 39, and cooperate therewith to clampingly engage the upper edges of the side rails 37 of the bed. Clamping screws 42 are shown mounted in the fixed jaws 39 for actuating the movable jaws 41, as will readily be understood by reference to Figures 11 and 12. The supporting arms 15 when mounted upon the side rails 37 of a bed equipped with a box spring 36, as above described, may be manipulated in identically the same manner as the supporting arms 15 of the form illustrated in Figures 1, 2 and 3.

In Figures 13 and 14, there is illustrated another method of mounting the supporting arms 15 of the bedding lifter upon a bed equipped with a box spring and mattress and wherein the side rails of the bedstead may not be suitably located or constructed to support the supporting arms.

In the form shown in Figures 13 and 14, the mounting brackets 21 of the supporting arms 15 are shown pivotally mounted upon spaced lugs 43 provided on the end members 44 of a relatively light frame, preferably composed of wooden slats or strips secured together at their ends by suitable metallic end members 44 by such means as screws or rivets 46. The open skeleton frame thus provided is adapted to be interposed between the mattress 8 and the box spring 36, as illustrated in Figure 14, whereby the supporting arms 15 of the device may be pivotally supported on the bed in proper relation to the size of the mattress, as will be understood by reference to Figure 14. The slats 45 of the skeleton frame are of such length as to properly position the supporting arms 15 with respect to the sides of the mattress.

In Figure 15 there is illustrated an arch-shaped member, generally designated by the numeral 47, comprising tubular sections 48 and 49 having their upper horizontal portions telescopingly engaged with one another whereby said member is adapted for longitudinal adjustment to vary the length of the member 47 in accordance to the width of the bed to which it is to be applied. The end portions of the tubular sections

48 and **49** are curved downwardly, and terminal elements **51** are secured thereto adapted to be received in the socket members **16** in a manner similar to the spaced legs of the arch-shaped member shown in Figure 3. The terminal elements **51** may be provided with cylindrical extensions adapted to be received in the lower ends of their respective tubular sections **48** and **49** and secured therein by welding or by suitable rivets.

If desired, the arch-shaped member **47** may be covered with a suitable fabric, not shown, to protect the individual's feet from directly contacting the metal of said member. In like manner, the intermediate portion of the arch-shaped member **12** may be covered with a suitable fabric, if desired.

In the drawings I have shown the supporting arms **15**, mounting brackets **21**, and the clamping elements as being constructed of cast metal as, for example, aluminum. In like manner, the spaced legs **14** of the arch-shaped member **12** are shown of cast metal. It is also to be understood that these parts may be otherwise constructed if desired without departing from the scope of the invention.

In the specification, the invention has been described as being used in connection with a bedstead and a mattress. It is to be understood that these terms are used in a broad sense and intended to apply to other articles or surfaces upon which an individual may lie or repose when seeking rest and slumber, and to which the invention may be applied for the purpose herein disclosed.

The novel bedding lifter herein disclosed has been found very practical in actual use and may be applied to most conventional forms and types of bedsteads. The supporting arms **15** and their mounting brackets **21** are very compact and do not project outwardly from the mattress but what they may readily be concealed beneath the bedding when the bed is made up. By securing the mounting brackets **21** to the side rails **6** of the bed spring adequate space is provided between the supporting arms and the sides and foot end of the bed spring to permit the usual bed sheets and other bedding to be tucked under the end of the mattress as is common.

When the bed is made up, as when not in use, the arch-shaped member **12** is preferably swung downwardly to its inoperative position, shown in Figure 3, whereby said arch-shaped member, in most instances, will not mar the appearance of the bed. The arch-shaped member **12** is so positioned in the bed when in its inoperative position that an individual, upon retiring, may readily swing said member upwardly into its upright operative position by engaging the upper horizontal bar thereof with a foot and shoving it downwardly towards the foot of the bed to the position shown in Figure 1 with the feet, as will be understood. If desired, the member **12** may be swung upwardly into operating position before retiring by inserting an arm under the bed covers and manually swinging it upwardly to the position shown in Figure 1. A flange **10** is preferably provided on the outer end of each arm **15** adapted to be engaged by the terminals of the legs of the arch-shaped member **12** to prevent the legs **14** of said member from axially moving in the guides **16** when they are engaged by an individual for the purpose of swinging the member upwardly into operative position.

It is to be understood that when the arch-shaped member is in its operative position, the terminals **18** of its spaced legs **14** will drop into

the fixed sockets **19** in the supporting arms **15** whereby the supporting member **12** will be locked in its operative position beneath the bedding. The novel bedding lifter herein disclosed, when in operative position, supports the bedding at the foot of the bed in a tent-like manner over the feet, whereby the feet are provided complete freedom from the weight of the bed covers and also whereby they are free to move about without restraint from the bedding.

Actual experience has proven that by relieving the feet of the weight of the bed clothes whereby the feet may be freely moved about without restraint, tends to stimulate blood circulation, an, as a consequence, individuals who frequently have difficulty in keeping their feet warm at night may find complete relief from such affliction by the use of the novel invention herein disclosed. Individuals suffering with hot, burning feet may also find relief at night by relieving the feet of the weight of the bedding.

It will be apparent to those skilled in the art that I have accomplished at least the principal objects of my invention, and it will also be apparent to those skilled in the art that the embodiments herein described may be variously changed and modified without departing from the spirit of the invention, and that the invention is capable of uses and has advantages not herein specifically described; hence it will be appreciated that the herein disclosed embodiments are illustrative only, and that my invention is not limited thereto.

I claim as my invention:

1. In combination with a bedstead comprising a spring provided with suitable side rails and having a mattress and bedclothes supported on the spring, a pair of mounting brackets having means for securing them to the side rails of the bedspring, a supporting arm pivotally secured to each mounting bracket, a socket member pivoted to the outer end of each supporting arm, an arch-shaped member having a horizontal portion adapted to be positioned beneath the bedclothes and having spaced legs having their terminal portions received in said pivotally mounted socket members, thereby to pivotally support the arch-shaped member upon said arms, said pivotally supported socket members permitting the arch-shaped member to be supported in upright operative bedclothes-lifting position when the bed is to be occupied, and means operable in connection with said pivotally mounted socket members for locking the arch-shaped member in operative position.

2. In combination with a bedstead comprising a spring provided with suitable side rails and having a mattress and bedclothes supported on the spring, a pair of mounting brackets having means for securing them to the side rails of the bedspring, a supporting arm pivotally secured to each mounting bracket and each provided at its outer end with a fixed socket, a socket member pivoted to the outer end of each supporting arm and adapted to be swung into alignment with the fixed sockets in said arms, an arch-shaped member having a horizontal portion adapted to be positioned beneath the bedclothes, said member having spaced legs, the terminals of which are adapted to be received in said pivotally mounted socket members to thereby pivotally support the arch-shaped member upon said arms, said pivotally supported socket members permitting the arch-shaped member to be swung upwardly to an upright operative

position whereby the terminals of its legs may engage in said fixed sockets and thereby lock the arch-shaped member in position to support a portion of the bedclothes at an elevation above the mattress.

3. In a device of the class described, a pair of supporting arms, clamping elements, for mounting said arms on the side rails of a bedspring, an arch-shaped member removably and pivotally supported on the outer ends of said arms and adapted to be engaged with the top bedclothes of a bed and support it in elevated position above the usual mattress of the bed to provide freedom of movement for a portion of an individual's body reposing on the mattress, and means carried by said clamping elements adapted to be inserted between the mattress and the bedspring to thereby prevent relative rotation of the clamping elements upon the side rails of the bedspring.

RUDOLPH T. ECKLUND.
